CLAIM

The ornamental design for a foldable cart, as shown and described.

DESCRIPTION

FIG. 1 is a perspective view of a foldable cart showing my new design where the foldable cart is in an unfolded state; FIG. 2 is another perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is a perspective view of the foldable cart where the foldable cart is in a folded state; FIG. 10 is another perspective view thereof; FIG. 11 is a front elevational view thereof; FIG. 12 is a rear elevational view thereof; FIG. 13 is a left side elevational view thereof; FIG. 14 is a right side elevational view thereof; FIG. 15 is a top plan view thereof; FIG. 16 is a bottom plan view thereof; FIG. 17 is an enlarged view of portion 17 shown in FIG. 1; and, FIG. 18 is an enlarged view of portion 18 shown in FIG. 7. The broken lines in the drawings depict portions of the foldable cart that form no part of the claimed design.

1 Claim, 18 Drawing Sheets
